HEATING SYSTEM FOR RAIL SWITCHES

Frederick H. Thompson, Jr., Chicopee, Mass.

Application May 21, 1936, Serial No. 80,999

12 Claims. (Cl. 158—96)

My invention relates to heating systems for rail switches, shown and described in my prior application, Serial Number 12,802, filed March 25, 1935, for improvements in Heating systems for rail switches, and the present application is confined particularly to the burner construction for such systems and is a continuation in part of said application.

An object of my invention is to provide a burner for rail heating systems which is simple and sturdy in construction, capable of being installed, removed, and operated by inexperienced labor, and adaptable for compact storage, when not in use.

This, and other objects and advantages of my invention will be more completely disclosed and described in the specification, the accompanying drawings, and the appended claims.

A preferred embodiment of my invention is illustrated in the accompanying drawings, in which:

Fig. 1 is an elevational view of one of the burner units.

Fig. 2 is a vertical, sectional view on the line 2—2 of Fig. 1.

Fig. 3 is a plan sectional view on the line 3—3 of Fig. 2.

Fig. 4 is a cross sectional view on the line 4—4 of Fig. 2.

Fig. 5 is a detail view, showing a heater installed for heating a railway switch.

Fig. 6 is a plan view of a burner, illustrating a modified form of cover construction for the burner wick.

Fig. 7 is a partial sectional view on the line 7—7 of Fig. 6.

Fig. 8 is a partial sectional view on the line 8—8 of Fig. 7.

Fig. 9 is a partial elevational view, partially in section, on the line 9—9 of Fig. 7.

Fig. 10 is a view similar to Fig. 6, illustrating a further modification of cover construction.

Fig. 11 is a partial sectional view on the line 11—11 of Fig. 10.

Fig. 12 is a view similar to Fig. 11, showing the halves of the cover raised.

Fig. 13 is a partial elevational view, showing the cover-operating levers.

Referring now to the drawings in detail, in which like numerals refer to like parts throughout:

One of the rails is indicated at 2, which is supported on a roadbed 8, in the usual manner. Oil burner units 9 are located beneath the rail 2. The burner units 9 are removably secured on pipe fittings 10.

Referring to Figs. 1-4, inclusive, the burner unit 9 is built up with an outer, cylindrical casing 19, an inner, cylindrical member 20, an annular ring member 21, channel-shaped in cross section, between the outer and inner cylinders 19 and 20, near the top edge of the member 20, a supporting plate 22 for the inner cylindrical member 20, a supporting ring 23 for the plate member 22, and a bottom, or base, plate 24, for the outer casing 19. These parts are welded, or otherwise secured together, to provide a strong, sturdy, and unitary structure. The inner, cylindrical member 20 is filled with a wicking material 25 which, during operation of the burner, is saturated with a liquid fuel. The member 20 projects slightly above the ring member 21, as shown at 20', to provide an annular, collecting channel 26 for ice, snow, or water, which may drop into the burner 9, and openings 27, in the outer casing 19, provide drainage for the channel 26, to the outside of the casing 19. The casing 19 projects above the member 20 to provide a barrier between the flame of the burner and the ties between which the burner is located. Openings 28, in the plate 22, and openings 29, in the ring 23, provide a free path for liquid fuel, within the outer casing 19. Openings 30, in the inner, cylindrical member 20, permit the liquid fuel to enter the member 20 from the casing 19, and thereby, saturate the wicking 25.

A plate 31, welded, or otherwise secured to the base plate 24 of the casing 19, has secured thereon a sleeve member 32 and a tapered valve member 33. The pipe fitting 10 is provided with an upwardly extending boss 34 and is formed with a tapered valve seat 35. When the burner 9 is assembled on the fitting 10, the upwardly extending boss 34 lies between the valve member 33 and the sleeve 32. The sleeve 32 is provided with lugs, or studs 36, which engage in the arc-shaped, bayonet slots 37, formed in the boss 34, to hold the burner in position on the fitting 10. The ends of the horizontal portions of the slots 37 provide stops for open and closed positions of the valve 33, as indicated in Fig. 4. The valve 33 is formed with a vertical, axial opening 38 which, at its upper end, registers with an opening 39, through the plates 24 and 31, and at its lower end, merges into a horizontal opening 40. A second, horizontal opening 41 is formed in the valve 33 with its axis at right angles to the axis of the opening 40. When the valve is in operating, or open position, as indicated in Fig. 2, liquid fuel entering the fitting 10 from the pipe 12 flows through the opening 40 and 55

also upward through the opening 38, into the casing 19. When the burner 9 is revolved 90 degrees, the valve 33 is turned to closed position, in which position, fuel entering the fitting 10 from the pipe 12, will flow through the opening 41 into the pipe 11, thereby continuing to supply other burners, if desired, in the system, but access to the casing 19, through the opening 38, will be shut off. By turning the burner 9 to a halfway position between open and closed position, the studs 36 will register with the vertical portions 37' of the slots 37, and the burner 9, including the sleeve 32 and valve 33, may be lifted and removed from the fitting 10.

15 A cover 42, movably supported above the wick chamber 20, serves to control the amount of oxygen available to the wicking 25 and to protect the chamber 20 and its contents from the drip of ice, snow, or water. The cover 42 is supported by means of the lug 43 on the diametrically located rod 44. The rod 44 is provided with a knob 46 and a thumb nut 47. The rod 44 is engaged in the oppositely disposed slots 48 formed in the outer casing 19. Moving this rod in the slots 48 will cause its opposite ends to move in opposite directions, as indicated by the arrows 49 in Fig. 3, thereby causing the cover 42 to descend toward the cylindrical member 20. As the top edge 19' of the casing 19 is intended to be located close to the under side of the switch rails, additional openings 50 may be provided in the casing 19 to permit entrance of sufficient air for efficient combustion. A bail 51, secured on the casing 19, provides for easy handling of the burner and for turning the same for insertion in and removal from the pipe fitting 10. A stud 52 is also secured on the plate 31 to provide means for turning the burner 9 in the fitting 10, when the burner is located under the switch rails and the bail is not available for use.

In Figs. 6, 7, and 8, I have illustrated a modified form of cover for the wick chamber 20. A shelf member 53, formed with side portions 54, is secured on the outside of the casing 19, and a slot 55 is formed in the casing 19 immediately above the shelf 53. A slide 56, formed with side portions 57, is slidably supported on the shelf 53 and guided by engagement of the side portions 57 with the sides 54 of the shelf 53 and with the wick-enclosing chamber 20. The slide 56 is adjustably secured on the shelf 53 by a stud 58 on the shelf 53, engaged in a slot 59, formed in the slide 56, and a wing nut 60. Openings 61 may be formed in the casing 19 to provide sufficient air to the wick chamber 20. With this form of cover, the area of flame derived from the wick chamber 20 may be regulated by covering a portion of the top of the chamber 20, and the flame may be extinguished by completely covering the chamber 20 with the slide 56. The sides of the slide 56 are tapered at 62 to provide a maximum of angle of revolution of the burner 9, between the ties 7.

A further modified form of cover is illustrated in Figs. 10, 11, 12, and 13. This cover is made in two semi-circular halves, 63 and 64, and the part 64 is provided with an offset and rabbeted lip portion 65 for overlapping the end of the part 63, when the covers are closed, as shown in Figs. 10 and 11. The parts 63 and 64 are hinged at 66 and 67, respectively, on rods 68 and 69, and these rods are pivotally supported in bosses 70 on the casing 19. Levers 71, secured on the rods 68 and 69, outside of the casing 19, provide means for 75 revolving the rods 68 and 69 and thereby raising

or lowering the covers 63 and 64, as shown in Figs. 12 and 13.

What I claim is:—

1. A burner for the purpose described comprising, inner and outer cylindrical members formed and assembled to provide an annular space between the same, means for connecting and spacing said members from each other, a base plate, a conductor for liquid fuel, a plug fixedly secured to the base plate of the burner and removably connected to said conductor and formed with an axial bore for conducting the liquid fuel from said conductor through the plug and into the space between the outer and inner members, the inner casing having openings for permitting the oil to flow from the outer to the inner casing, said inner casing having wick material therein for absorbing said liquid fuel.

2. In a liquid fuel burner, inner and outer casing members, a ring member, the outer casing being secured to the inner casing and spaced therefrom by said ring member, said outer casing being provided with oppositely inclined slots, the inner casing extending above the ring member and having a wick therein, a cover for closing the upper end of the wick-receiving member said cover being mounted for movement toward and away from said inner casing, a rod in said slots on which said cover is secured, for varying the position of the cover, whereby the rate of combustion of the liquid fuel in the burner is controlled, said outer casing being extended above the upper edge of the inner casing.

3. A burner for the purpose described comprising, inner and outer members, ring means for connecting and spacing said members from each other, a conductor for liquid fuel, communicating means between said conductor and said outer member, the inner member having openings for permitting the oil to flow from the outer member into the inner member, said inner member having wick material therein, a cover for the inner member, and means for moving the cover onto and away from the top of the inner member, said means comprising slots in the outer member and a rod engaged in said slots and connected to the cover.

4. A burner construction for the purpose described having, in combination, inner and outer cylinders, a loosely massed wick material in the inner cylinder, means for spacing the cylinders relative to each other comprising a ring member located adjacent the upper edge of the inner cylinder, a cover for closing the upper end of the inner cylinder, the outer cylinder having openings located above the ring member, and means for conducting liquid fuel to the wick-material in the inner cylinder.

5. A burner apparatus for the purpose described comprising, a cylindrical outer casing, a cylindrical inner casing, ring means for spacing one casing from the other, an oil absorbent material in said inner casing, a conductor for a liquid fuel provided with an outlet port, said inner casing being provided with openings for permitting a flow of liquid fuel into the inner casing from said outer casing, fuel conducting means between said outer casing and the outlet port in said conductor.

6. A burner for the purpose described comprising vertically positioned cylindrical inner and outer members open at the top, ring means for connecting and spacing said members from each other, a base plate connected to the said outer member and having an opening, a conductor of

liquid fuel, a plug fixedly secured to the base plate of the burner and formed with a passageway communicating with said conductor whereby the fuel may enter the space between

- 5 the inner and outer members, the inner member being provided with openings communicating with said space, wick material in said inner member, a cover for the inner member, and means for moving the cover relative to the open
 10 top of said inner member for varying the heating effect of the burner and for protecting the wick material from rain and snow.

7. A burner for the purpose described comprising inner and outer vertically positioned cylinders open at the top and assembled to provide an annular space between them, ring members for connecting and spacing said cylinders, a conductor for liquid fuel, a plug on said outer cylinder formed with an opening communicating
 15 with said conductor, a wick material loosely massed in said inner cylinder, said inner cylinder being provided with ports communicating with said annular space, said outer cylinder extending above said inner cylinder and being provided
 20 with openings communicating with the space above said inner cylinder, cover means for closing the top of said inner cylinder, and means for operating said cover means.

8. In a burner construction for the purpose described, inner and outer cylinders open at the top, a ring member for spacing said cylinders, hinged cover members for closing the top of said inner cylinder, and means for operating said cover members to open and close them, said
 30 outer cylinder being provided with a plurality of openings located above said ring member.

9. In a burner construction for the purpose described, inner and outer cylinders, open at the top, a ring member for spacing said cylinders, 40 semi-circular flanged cover members for closing the top of said inner cylinder, and means for operating said covers to open and close them, said outer cylinder extending above said inner cylinder to enclose said cover members when said
 45 cover members are in open position, said outer cylinder being provided with openings above said ring member.

10. A burner for the purpose described comprising inner and outer vertically positioned cylinders assembled to provide an annular space between them and a space between the bottom of the inner cylinder and the bottom of the outer cylinder, ring members for connecting and spacing said cylinders, a conductor for liquid fuel, a nipple on the bottom of said outer cylinder and communicating with said conductor and the space between the bottoms of said cylinders, 10 a wick material loosely packed in said inner cylinder, said inner cylinder being provided with ports communicating with said annular space, oppositely hinged cover members for closing the top of said inner cylinder, and means for operating said cover members, each independent of the other, said outer cylinder extending above said cover members when said cover members are open.

11. In a liquid fuel burner for heating railway switches, an outer cylindrical casing, an inner cylindrical casing, said casings being coaxial and spaced to provide an annular chamber between them, said outer casing being provided with an opening in its side and aligned with the top 25 of said inner casing, means for closing the upper end of the inner casing comprising a slidable plate located in the opening of the outer casing, a support for said plate for guiding the same, and means for securing the plate in different 30 positions of adjustment over the upper end of the inner casing.

12. A burner construction for the purpose described comprising an outer open-topped cylindrical casing, an inner open-topped cylindrical 35 casing positioned within said outer casing and relatively smaller in diameter than said outer casing, whereby an annular chamber is provided between said casings, the inner casing being filled with loosely massed wick material, means for 40 conducting liquid fuel into said annular chamber, said inner cylinder being formed with a plurality of openings serving as communicating means between said wick material and said annular chamber.

45

FREDERICK H. THOMPSON, JR.
